PAGE END INDICATOR

Louis M. Llorens, New York, N. Y.

Application May 22, 1934, Serial No. 726,929

2 Claims. (Cl. 197—189)

This invention relates to line indicators, or page end indicators, for use in indicating on a typewriter, adding machine, or other device using a rotary platen, when the paper or record material is nearing exhaustion, and for further indicating the amount of record material still available.

One of the principal objects of the invention is to produce a device of this general character, 10 consisting of a few simple parts, cheap to manufacture, easy to assemble, and highly efficient for the purpose for which it is designed. Other objects will be apparent from the following description and claims.

15 These objects are attained by the mechanism shown in the accompanying drawing, in which Fig. 1 is a somewhat diagrammatic view of a typewriter with the present invention in place thereon.

20 Fig. 2 is a right hand end view of the invention, showing the parts in the position they assume when the record material is entered in the machine.

Fig. 3 is a view similar to Fig. 2, but showing 25 the parts in the position assumed when the record material is nearing exhaustion.

Fig. 4 is an exploded perspective view of the several portions of the mechanism.

Fig. 5 is a fragmentary section taken substantially on line 5—5 of Fig. 2.

Like characters of reference refer to like parts in all views.

While the invention has been shown as applied to a standard typewriter, it is quite obvious that 35 it may be applied to adding machines, stenographic machines, and like structures in which a cylindrical platen is used.

Referring to the drawing in detail, 10 represents a standard typewriter generally, which is 40 provided with the usual cylindrical printing platen 11 which is rotatably supported upon the usual carriage frame indicated at 12.

At the right hand end, the platen 11 is reduced in diameter as shown at 13, and has attached to 45 it a plate 14 formed with friction-drive fingers 15. Over these fingers 15, an indicator drum 16 is slipped. Drum 16 is provided with indicia as at 17, these numerals being arranged one line-space apart. Drum 16 is formed with a broad bearing

50 18, and with inner and outer lugs 19 and 20. Fingers 15 press against the inner surface of drum 16, and tend to rotate the drum with the platen.

Over drum 16 and the reduced portion 13, 55 passes a cylindrical member 21 formed with a sight opening 22, and openings 23 and 24 for a purpose to be later set forth. The indicia 17 may be viewed through opening 22 when drum

16 is permitted to turn. The cylinder 21 is provided with a hub 25 on which the bearing 18 rests, as clearly seen in Fig. 5.

Secured to cylinder 21 is an anchorage member having arms 26 and 27 resting against the carriage frame 12, so as to prevent member 21 from turning with the platen. This anchorage member is formed with a springy finger 28, which constantly presses a wire 29 toward the member 21. Wire 29 is pinned or otherwise secured to the anchorage member as at 30. Wire 29 has its free end formed into forks 31 and 32. Fork 31 is bent so as to form a V-shaped rider at 33, and fork 32 is bent so as to terminate in a stop element at 34. With the parts assembled, the rider 33 is in register with opening 24, and stop 34 is in the vertical plane of stops 19 and 20, fork 32 being extended through aperture 23.

The operation of the above parts is as follows:—Starting with no paper in the machine, 20 stop 34 is in the path of stop 19, which it intercepts so as to hold drum 16 against turning. In this position a blank or unnumbered portion of drum 16 is visible through opening 22. Upon inserting a sheet of paper (indicated at 35 in Figs. 2 and 3), the sheet in passing under rider 33, forces the entire member 29 rearwardly, thereby bringing stop 34 into the path of stop 20. Drum 16 may now move one step, bringing stop 20 against stop 34, as in Fig. 2. At this time a 30 blank portion of drum 16 is seen through opening 22. The parts remain thus until the paper nears the end, when the rider 33 drops into opening 24. As this happens, stop 34 passes between stops 19 and 20, and drum 16 is free to rotate 35 with the platen to expose indicia 17 through the sight opening 22. This indicates to the operator the number of lines which may still be printed before the paper is exhausted.

What I claim as new, and desire to secure by 40 Letters Patent is:

1. The combination of a rotatable platen, an indicating drum, connecting means between said platen and drum permitting simultaneous and relative movements of the platen and drum, stops 45 on said drum, and means cooperative with said stops and record responsive for holding said drum against movement and releasing said drum for movement with said platen.

2. The combination of a rotatable platen, an 50 indicating drum, connecting means between said platen and drum permitting simultaneous and relative movements of the platen and drum, stops on said drum, and a spring-pressed record responsive stop cooperative with said stops for 55 holding said drum against movement and releasing said drum for movement with said platen.

LOUIS M. LLORENS.
